DESIGN FOR A JEWELRY STAND

Henry Leonard Oblein, Chili, N. Y.

Application September 11, 1945, Serial No. 122,012

Term of patent 14 years

(Cl. D80—9)

To all whom it may concern:

Be it known that I, Henry Leonard Oblein, a citizen of the United States of America, residing in the town of Chili, in the county of Monroe and State of New York, have invented a new, original, and ornamental Design for a Jewelry Stand, of which the following is a specification, reference being had to the accompanying drawing, forming part thereof.

Fig. 1 is a top plan view of a jewelry stand, showing my new design;

Fig. 2 is a side elevational view thereof; and
Fig. 3 is a perspective view thereof.

I claim:

The ornamental design for a jewelry stand, substantially as shown.

HENRY LEONARD OBLEIN.
